UNITED STATES PATENT OFFICE.

ROBERT RIMMER, OF WIGAN, ENGLAND.

GOLF PUTTER.

Application filed July 5, 1923. Serial No. 649,694.

To all whom it may concern:

Be it known that I, ROBERT RIMMER, a subject of the King of Great Britain, residing in Wigan, in the county of Lancaster and Kingdom of England, have invented certain new and useful Improvements in Golf Putters, of which the following is a specification.

This invention relates to an improved golf 10 putter.

According to the invention the putter is so shaped and loaded that the centre of gravity of the head is near to the shaft. This may be accomplished by internally loading the 15 head, for example, with lead or other metals. Further, the tip of the head may be cut away or scolloped at the back of the striking face, either above, or underneath so that weight is removed from the toe.

20 A preferred form of the invention will now be described with reference to a metal putter, for example, of aluminium.

In the drawings:—

Figure 1 shows an elevation of the head of 25 the club looking towards the striking face.

Figure 2 is an end elevation of the head, and

Figure 3 is a plan of the head.

The club head 1, which may be made in 30 any convenient way, is provided with an internal cavity 2 which may be filled with lead through the aperture 3. The excess of lead is removed and the lead in the aperture 3 finished off level with the bottom 4 of the 35 head. The club head is attached in the usual manner to the shaft 5. The tip of the head is cut away or scolloped at 6 in the manner shown, i. e. the section removed from the upper surface of the head is preferably the 40 quadrant of a circle.

A thin brass or other metal strip 7 is arranged transversely across the head to give alignment for the stroke.

The principle of the invention is that by 45 bringing the centre of gravity near to the shaft, there is less tendency for the horizontal portion of the head to oscillate round the shaft as axis.

50 The invention particularly deals with golf putters of what may be termed the standard type i. e. in which the head does not project rearwardly of the line of the shaft.

The weight is preferably between the shaft and the centre of the club, and centrally of the club in transverse section i. e. behind the 55 line of the shaft.

I declare that what I claim is:—

1. A golf putter comprising a shaft and a head connected thereto, said head being loaded by a fixed weight situated wholly between the shaft connection to the head and the center of the head, the center of gravity of the weight being behind the line of the shaft.

2. A golf putter comprising a shaft and a connected head having the face substantially in line with the line of the shaft, said head being loaded with a weight located wholly between the shaft connection to the head and the center of the head, the 70 center of gravity of the weight being behind the line of the shaft.

3. A golf putter comprising a shaft and a connected head, said head having a putting face substantially in line with the line of the shaft, said head being loaded with a weight located wholly between the shaft connection to the head and the center of the head, the center of gravity of the weight being behind the line of the shaft, that portion of the 75 tip of the head to the rear of the putting face being cut away.

4. A putter comprising a head and a connected shaft, said head having a putting face substantially in line with the line of the shaft, and a strip disposed substantially transversely across the center of the head to give alinement for the stroke, said head having an interior cavity filled with lead located between said strip and the connection to the shaft, said cavity terminating at the face of the club in a restricted outlet so as to permit molten lead to be poured into said cavity.

In witness whereof, I have hereunto signed 95 my name this 22 day of June 1923, in the presence of two subscribing witnesses.

ROBERT RIMMER.
